UNITED STATES PATENT OFFICE.

THOMAS DANQUARD, OF NEW YORK, N. Y., ASSIGNOR TO AUTOPIANO COMPANY, OF NEW YORK, N. Y., A CORPORATION OF NEW YORK.

AUTOMATIC MUSICAL INSTRUMENT.

No. 872,611.

Specification of Letters Patent.

Patented Dec. 3, 1907.

Application filed May 10, 1905. Serial No. 259,700.

To all whom it may concern:

Be it known that I, THOMAS DANQUARD, a citizen of the United States, residing at New York, in the county of New York and State 5 of New York, have invented a new and useful Automatic Musical Instrument, of which the following is a specification.

This invention relates to that class of automatic musical instruments which are controlled by rolls or strips of perforated paper.

The especial object of this invention is to provide simple, convenient and efficient connections for controlling the music sheet so as to permit sharply defined phrasing and accenting of a musical composition and to provide an adjustable stop mechanism therefor.

To these ends, this invention consists of a finger-key and its connections for momentarily stopping the winding motor as herein-after described and more particularly set forth in the claims at the end of this specification.

In the accompanying two sheets of drawings, Figure 1 is a sectional view of sufficient parts of an automatic piano-player or similar musical instrument to illustrate the application of this invention thereto, and Fig. 2 is a front view partly broken away showing the relation of the finger-key to the winding mechanism.

In playing upon automatic piano-players of that class in which a pneumatic striking action is controlled by a strip of perforated paper, it has been found that it is desirable to interrupt and momentarily stop the travel of the music sheet whenever a marked phrase or accented chord is to be played. This has heretofore ordinarily been done by shifting the tempo-lever.

The production of retarded effects by shifting the tempo-lever of a piano-player requires a considerable degree of skill, and is apt to be objectionable as the tempo-lever is 45 not always returned accurately to the same position when the playing is to be resumed at normal speeds.

In an automatic musical instrument constructed according to this invention, instead 50 of relying upon the manipulation of the tempo-lever to produce retarded effects, I have provided a finger-button which is located in convenient position in front of the music-roll, and which is adapted to be readily controlled by the finger of the operator to

give a momentary pause to the travel of the music-sheet whenever a retarded effect is desired.

Referring to the accompanying drawings for a detail description of an apparatus embodying this invention, as shown in Fig. 1, 10 designates the casing of a piano-player constructed according to this invention. Mounted inside the casing and in the bottom part thereof are the usual feeders, each of 15 which consists of the inclined board 11 and the swinging board 12 which is connected by a link 13 to a pedal 14. The feeders exhaust the air from a main air chamber 15 which may be connected to supply a pneumatic 20 striking action in the ordinary manner, which need not be herein shown or described.

Leading from the main air chamber 15 is a passage 16 which opens to the inside of a pneumatic governor device having a hinged plate 17 which is normally held open by a spring, but which when collapsed will close the passage 16 to automatically govern the wind motor in the usual way. Also opening 25 from the inside of the pneumatic governor device is a passage 18.

As illustrated most clearly in Fig. 2, the passage 18 opens into the wind-box of an ordinary wind-motor and is controlled by the tempo valve 19, which may be set to different positions according to the tempo or speed at which a musical composition is to be played. The wind motor herein illustrated comprises the ordinary motor-pneumatics 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1698, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741,

tary stoppage or retard of travel of the music-sheet is desired. In the use of a piano-player as thus equipped, the finger of the operator strikes directly down upon the 5 finger button, and has a direct locking action upon the pneumatic governor device, and I have found that by means of these connections an accurate and direct control may be maintained of the travel of the music 10 sheet.

In assembling the parts of a mechanism for controlling a piano-player according to this invention, it is very desirable that some means of adjustment may be provided for 15 regulating the height that the finger key A extends above its top board and length of the stroke that must be given to the finger key. In order to stop the music sheet I have provided means for accomplishing this by 20 providing a stop-rod having a button 25 adjustably threaded thereon. By screwing in the button 25 the opening motion of the pneumatic governor device may be limited so that a comparatively short stroke on the 25 finger button A will serve to hold the pneumatic governor device closed, while by screwing out the regulating button 25 the pneumatic governor device may be allowed any desired amount of opening which may be 30 found to be necessary for successful operation in the use of a mechanism constructed according to this invention.

In order to produce an accented or marked effect, the operator will press more powerfully upon the pedals just before the perforations which correspond to a chord which it is desired to accent or sound louder, come over the perforations in the tracker-board and simultaneously with the sounding of the 40 note the operator pushes down on the retard and accent key A, momentarily stopping the travel of the music sheet to produce the

same kind of effects which are produced by involuntary pauses made by a skillful performer in accenting a note or chord while 45 playing a piano by hand.

I am aware that changes may be made in applying my invention to different styles and constructions of piano-players or similar musical instruments. I do not wish, therefore to be limited to the construction herein shown and described, but

What I do claim and desire to secure by Letters Patent of the United States is:—

1. In a musical instrument, the combination of a paper winding mechanism and a wind motor, of a pneumatic governor mechanism for the wind motor comprising a collapsible pneumatic having a movable member, a finger key connected to hold the movable member of the pneumatic closed when the retarded effect is desired, a stop rod fixed in stationary position and connected with the movable member of the pneumatic, and a button adjustably mounted on the stop rod 55 for limiting the stroke of the finger key.

2. In an instrument of the class described, the combination of the paper winding mechanism, a wind motor, a pneumatic governor mechanism for the wind motor comprising a 60 collapsible pneumatic having a movable hinged member, a finger key connected to hold the movable member of the pneumatic closed when a retard effect is desired, and an 65 adjustable stop mechanism limiting the 70 stroke of the finger key.

In testimony whereof I have hereunto set my hand, in the presence of two subscribing witnesses.
